AUTOMATIC WEFT-REPLENISHING LOOM

William Alexander Dickie, Frank Corbyn Hale,
and William Howarth, Spondon, near Derby,
England, assignors to Celanese Corporation of
America, a corporation of Delaware

Application April 14, 1931, Serial No. 530,018
In Great Britain June 12, 1930

3 Claims. (Cl. 139—232)

The present invention relates to weft-replenishing looms, i. e., looms in which weft is automatically supplied on exhaustion. The invention is particularly concerned with the weft replenishment of looms which have a change-box mechanism for the insertion of different kinds of weft for mixing or other purposes.

According to the invention, a weft replenishing loom comprises a change-box motion, a shuttle magazine containing as many kinds of weft as there are shuttle boxes, and means for replacing a shuttle whose weft is exhausted by a shuttle containing the same kind of weft.

The means for effecting the replacement of a spent shuttle by another shuttle containing similar weft are set into operation by means of suitable feeler mechanism which detects the exhaustion of the weft in any of the shuttles. For example a mechanical or electrical weft detector device may be provided for each shuttle and adapted to set in operation mechanism which removes a spent shuttle from the shuttle-box and transfers a full shuttle from the magazine to the box, the selection of the shuttles from the magazine being effected from the change-box motion, or even from the feeler mechanism in cases when each shuttle has its own detector.

The replacement of a shuttle is preferably carried out with the loom at rest, in order to avoid danger to the loom mechanism, breakage of shuttles, or damage to weft or warp.

It is convenient in change-box looms to detect the approaching exhaustion of weft in the shuttle which has just moved out of picking position, since the movement of the shuttle itself can be used to bring the weft into contact with the feeler mechanism. It is consequently necessary to delay changing of the spent shuttle until that shuttle is again picked into the shuttle box on the magazine side of the loom, and the invention therefore comprises means to give the requisite delay, which in the case of a two-box loom has to extend over three picks.

The invention enables weaving on crêpe looms or other looms using two or more different kinds of weft to be carried out with the advantages obtainable by the use of shuttle-changing mechanism for replenishing the weft. Thus, the weft is subjected to little stress, either during shuttle-changing or during picking, which is particularly important when artificial silk is used as weft, and there is no danger of the end of weft in a spent shuttle being drawn into the fabric on the next pick.

The invention will now be described as ap-

plied to a two box loom with reference to the accompanying drawings, but it is to be understood that the following description is given by way of example only, and is in no way limitative.

In the drawings:

Fig. 1 is an end elevation of the loom showing the change-box mechanism, the shuttle magazine, and the shuttle-selecting mechanism;

Fig. 2 is an end elevation of the magazine showing details of the shuttle-releasing mechanism;

Fig. 3 is a further magazine detail;

Fig. 4 is an end elevation of the loom showing the detector mechanism;

Fig. 5 shows the electrical circuit of the detector mechanism;

Fig. 6 is an end elevation of the loom showing the means employed for putting the shuttle-changing mechanism into operation;

Fig. 7 is a front elevation of the mechanism shown in Fig. 6;

Fig. 8 is a plan of the starting handle and associated parts shown in Fig. 7;

Fig. 9 is a plan of part of the mechanism shown in Figs. 6 and 7;

Fig. 10 is an end elevation of the loom showing the shuttle-changing mechanism; and

Fig. 11 is a plan view of the loom restarting mechanism shown in Fig. 9.

Referring to Fig. 1, the two movable shuttle boxes 12 at one side of the loom are shown as operated by a rod 13 connected to one end of a lever 14 pivoted on a shaft 15 and oscillated by an eccentric 16 under the control of a Geneva mechanism 17 which causes the boxes to be moved up and down after every two picks. The shaft 15 runs the length of the loom and at the end remote from the lever 14 carries a lever 18 which is connected by a link 19 and lever 20 to a rod 21 carrying a block 22 which is thus caused to rise and fall in accordance with the movement of the boxes 12.

Mounted above and below respectively the movable shuttle boxes 12 are detector devices 23 each comprising a pair of movable metallic plungers 24 adapted to be pressed against the yarn on the pirns 25 by the movement of the boxes 12. Thus, when the boxes are moved upwardly to bring the lower box to the level of the shuttle race 26, the upper plungers 24 are pressed against the yarn in the upper shuttle. Similarly, when the boxes are lowered, the lower plungers 24 are pressed against the yarn in the lower shuttle. A plunger of each pair is connected by a lead 27 to one terminal of an elec-

tro-magnet 28 and the other plunger of each pair is connected by a further lead 29 to a battery 30 or other source of current which in turn is connected by a lead 31 to the other terminal 5 of the magnet 28.

The pирn tubes may be made of metal, or provided with a metallic strip or other metallic coating so that on exhaustion of the weft, contact is permitted between the pair of plungers 10 24 of any one detector when they are pressed against the exhausted pирn. Consequently, the circuit of the magnet 28 is completed, and this serves to bring a catch 32 from the position shown in full lines in Fig. 5 to the position 15 shown in dotted lines.

The catch 32 and the magnet 28 are mounted below the shuttle race 26 in such a position that on the forward movement of the lay the catch 32 passes above a notched block 33 while the 20 magnet remains de-energized. On actuation of the catch 32 by the magnet 28, the catch is adapted to engage the notched block 33 and so operate mechanism which stops the loom and sets the shuttle-changing mechanism into operation. 25 Since, however, at the time when weft exhaustion has been detected that particular shuttle has moved out of picking position, stoppage of the loom has to be delayed until that shuttle is again picked to the other side of the loom, i. e. after 30 three picks. The lever 34 carrying the block 33 is therefore pivotally mounted at 35 on a bell-crank lever 134 which is operated by a cam 135 to move the block 33 out of the path of the set catch 32 on the first forward movement of the 35 lay after detection of weft exhaustion, and to move it again into the path of the catch on the next pick, the catch of course remaining set by the continued engagement of the plungers 24 with the exhausted pирn. The other shuttle has 40 by this time returned to its box 12 and the spent shuttle is picked to the other side of the loom, which is then stopped.

To stop the loom, the lever 34 is provided at its upper end with an extension 36 which, when the lever 34 is rocked about its pivot 35 by the catch 32, moves an arm 37 to release the starting handle 38 from a retaining catch 39. The handle 38 is then free to spring along the slot 40 to stop the loom through a link 41 connected to a lever 42 operating a clutch 43 on the driving shaft 44 of the loom, as shown in Figs. 6 and 7.

Referring now to Fig. 4, it will be seen that the lower end of the lever 34 engages with a pin 45 on one arm of a bell-crank lever 46 whose other 55 arm is connected to a link 47. This link is in turn connected to a lever pivoted at 48 and consisting of two parts 49, 50 pivoted together at 51 and connected by a spring 52. Integral with the part 49 is a catch 53 which tends to move in a counter-clockwise direction by reason of the upward pull of the link 47 caused by engagement of the lever 34 by the catch 32.

The purpose of the catch 53 is to release mechanism which will set the shuttle-changing mechanism in operation, and in order to ensure that this action cannot take place except by reason of weft exhaustion, means are provided to prevent movement of the catch in any other circumstances. For this purpose a latch 54 pivoted at 65 55 is supported horizontally by a cam 56 which engages a pin 57 on the latch, and the end of the latch is arranged to oppose a projection 58 on the catch 53 except for a short instant when the loom is being stopped due to weft exhaustion.

70 The cam 56 is connected by a link 59 to the

brake arm 60 which in turn is connected by a link 61 through a lever 62 having a lug 63 extending over the arm 37 of the loom-stopping mechanism. A bowl 64 on the starting handle 38 engages the lever 62 on starting of the loom and causes the lug 63 to rest on the arm 37 to keep the brake rod raised and the brake band 65 free. When the loom is stopped by engagement of the rod 36 with the arm 37 the lug 63 is freed and the brake arm 60 falls under the influence of the weight 66 to 10 apply the brake. At the same time the cam 56 is rocked and momentarily raises the latch 54 above the projection 58 to permit the counter-clockwise movement of the catch 53 under the pull of the link 47. It will be seen, therefore, 15 that should the link 47 be pulled at any other time than when the brake is being applied due to weft exhaustion, the catch 53 is unable to move, the lever comprising the parts 49, 50 merely being broken about the pivot 51 against the action 20 of the spring 52.

The catch 53 is adapted during running of the loom to prevent movement of a lever 67 pivoted at 25 68 and tending to move in a clockwise direction as viewed in Fig. 6 under the action of means to be described later. Release of the catch 53 frees the lever 67 and permits the setting in motion of a shaft 69 which drives the shuttle changing mechanism. The shaft 69 carries a disc 70 facing a further disc 71 loosely mounted on the 30 shaft and driven by gears 72 and a chain drive 73 from the driving shaft 44 of the loom, which, of course, continues to run even when the clutch 43 is de-clutched on stopping of the loom.

A lever 74 is pivoted across the face of the disc 70 remote from the disc 71 and the end 75 of the lever 74 passes through a hole in the disc 70 and is constantly urged towards the disc 71 by means of a spring 76. The disc 71 has a circular series of holes adapted to receive the end 75 of the lever 74. The spring 76 is prevented from causing the part 75 to enter the disc 71 by means of a shoe 77 mounted on one end of a rod 78 connected by a bell-crank lever 79 and links 80 to the lever 67. When, however, the lever 67 is released by movement of the catch 53, the spring 76 is freed from the restraint of the shoe 77 and forces the part 75 into engagement with the disc 71, so setting the shaft 69 into motion.

The shaft 69 carries three cams 81, 82, 83 50 adapted (1) to raise the shuttle box front 84 at the side of the loom at which shuttle changing takes place to eject the exhausted shuttle by means of the ejector 85 actuated by lifting of the box front, (2) to move the conveyor lever 86 from 55 the position in which the conveyor 87 rests below the magazine 88 to the open shuttle box so as to transfer a shuttle released from the magazine to the shuttle box in replacement of the exhausted shuttle, and (3) to re-start the loom as will be 60 described later.

The magazine 88 comprises two chutes 89, 90 containing shuttles corresponding to the two kinds of weft being laid in the fabric. The shuttles are retained in position by catches 91 pivoted at 92 at each end of the magazine and projecting through the end walls 93 of the magazine. These catches pivotally support levers 94 connected by links 95 and bell-crank levers 96 to rods 70 97 projecting laterally from the end of the magazine opposite the rod 21. The movement of the rod 21 in accordance with the movement of the shuttle boxes 12 moves the block 22 into line with the rod 97 appropriate to the part of the maga- 75

zine corresponding to the shuttle which is to be replaced.

When the shuttle is exhausted an eccentric 98 on the cam shaft 69 acting through a rod 99, bell-crank lever 100, link 101 and bell-crank lever 102, presses a pin 103 on the lever 102 against the rod 21 and causes the block 22 to strike the appropriate rod 97, so withdrawing the catches 91 from the ends of the corresponding part 89 or 90 of the magazine 88. The lowermost shuttle is thus allowed to fall to the bottom of the magazine. At the same time a catch 104 on the lever 94 by which the catch 91 is operated enters each end of the magazine to prevent the remaining 15 shuttles from falling.

On the return movement of the block 22 under the action of the spring 105 pressing against the rod 21, the catches 91 re-enter the magazine and the catches 104 are withdrawn to allow the remaining 20 shuttles to fall on to the catches 91.

The shuttle which has been released falls on to a support 106, being guided thereto by a light spring blade 107. The support 106 is carried on an arm 108 pivoted on a shaft 109, and normally 25 closes the open bottom of the magazine 88. The first movement of the conveyor arm 86 to transfer a new shuttle to the shuttle box is towards a stop 110 carried by the arm 108 so as to bring the arm to the dotted position shown in Fig. 2 30 and to remove the support 106 from beneath the released shuttle, which thereupon falls on to the conveyor 87. The conveyor arm next moves in the opposite direction, that is towards the shuttle box of the now stationary lay, which has been 35 stopped at back-centre. In the meantime the cam 81 has lifted the shuttle box front through a rod 111 and the box front in turn has actuated the ejector 85 to remove the exhausted shuttle. The shuttle box is thus free to receive a new 40 shuttle.

The conveyor arm 86 then returns to its original position, the shuttle box front 84 descends and the loom is ready to be restarted. Means are preferably provided to release the swell during 45 insertion of the new shuttle and until the box front has been properly lowered.

Restarting is effected by means of a lever 112 actuated by the cam 83 and operating a rod 113 having a collar 114 which engages a catch 115 pivotally mounted on a tubular member 116 in which the rod 113 slides. The member 116 is connected by a bell-crank lever 117, link 118, lever 119 and rod 120 to the starting handle 38 of the loom. In the event of the shuttle box front not being correctly lowered to close the shuttle box, as in the case of improper transfer of the new shuttle from the conveyor to the shuttle box, the rod 111 is prevented from rising to its proper position, and a pin 121 carried by the rod remains in engagement with the tail 122 of the catch 115 to prevent the catch from being engaged by the collar 114. Thus the connection between the rod 113 and the starting handle 38 is broken, and the loom cannot be restarted.

The various operations just described are carried out during one revolution of the shaft 69. Towards the end of this revolution, the tail of the lever 74 employed to clutch together the discs 70, 71 is carried beneath the shoe 77, which being

free from the influence of the spring 76 has been pushed towards the disc 70 under the action of a spring 123 connected to the lever 67. The lever 67 has also been lowered into position for re-engagement by the catch 53 which returns 5 to its original position under the influence of the weight of the link 47 and associated parts. The shoe 77 is thus rendered immovable so that the tail of the lever 74 is pressed towards the disc 70 and the part 75 of the lever 74 is withdrawn 10 from engagement with the disc 71, with the result that the shaft 69 is brought to rest.

What we claim and desire to secure by Letters Patent is:—

1. In a loom the combination of the lay having 15 shifting shuttle boxes at one end adapted to receive a plurality of alternately active shuttles, with a filling feeler positioned to continuously feel for filling in the inactive shuttle so long as such shuttle remains in inactive position, an 20 electric circuit closed by said feeler when it detects substantial exhaustion of the filling supply, a member normally moving in a fixed path, a latch operative to effect a predetermined change in the operation of the loom, and means including 25 an electro-magnet in the said circuit for establishing an operative connection between the latch and the said member after the circuit has remained closed not less than one pick.

2. A loom comprising a lay having shifting 30 shuttle boxes at one end adapted to receive a plurality of alternately active shuttles, filling feelers each positioned to feel for filling when the corresponding shuttle is in inactive position, an electric circuit closed by either of said feelers 35 when it detects substantial exhaustion of filling supply in a shuttle, an electro-magnet included in said circuit, a latch operable by the electro-magnet, a member normally moving at alternate picks into and out of the vicinity of the latch, 40 means controllable by said member to effect a predetermined change in the operation of the loom, and means controlled by the beat of the lay to bring the member into position for operative connection to be established between the 45 latch and the member after the circuit has been closed not less than one pick.

3. A loom comprising a lay having shifting shuttle boxes at one end adapted to receive a 50 plurality of alternately active shuttles, filling feelers each positioned to feel for filling when the corresponding shuttle is in inactive position, an electric circuit closed by either of said feelers when it detects substantial exhaustion of filling supply in a shuttle, an electro-magnet included 55 in said circuit, a latch carried by the lay and operable by the electro-magnet, a member mounted independently of the lay and normally moving at alternate picks into and out of the vicinity of the latch, and means controllable by said member 60 to effect a predetermined change in the operation of the loom, the beat of the lay serving to establish operative connection between the latch and the member after the circuit has been closed not less than one pick.
